(57) **CLAIM**

The ornamental design for an arm attachment device for heavy bag, as shown and described.

DESCRIPTION

FIG. 1 is a front perspective view of an arm attachment device for heavy bag, showing my new design;

FIG. 2 is a front elevation view thereof;

FIG. 3 is a rear elevation view thereof;

FIG. 4 is a left elevation view thereof, the right elevation view thereof;

FIG. 5 is a top plan view thereof, the bottom plan view being an identical image thereof; and,

FIG. 6 is a perspective view of the arm attachment device for heavy bag, shown in use.

The dash-dash-dot evenly sized broken lines showing a heavy bag in FIG. 6 and the attached arms throughout the figures depict environmental subject matter that forms no part of the claimed design, while the remaining dash-dash-dot evenly sized broken lines shown in the drawings depict portions of the arm attachment device for heavy bag that form no part of the claimed design.

The dash-dot-dot lines in FIGS. 1-4 and 6 depict the boundaries of the claim within the encircling portion; and it is understood that the claim extends to these boundaries that form no part of the claimed design. The breaks in the encircling portion of FIG. 5 correspond to the boundaries seen in the other figures.

1 Claim, 4 Drawing Sheets
